UNITED STATES PATENT OFFICE.

ERNEST DAVIS, OF CHICAGO, ILLINOIS. ASSIGNOR, BY MESNE ASSIGNMENTS, TO LIBERTY NATIONAL BANK, TRUSTEE.

PRESSING-MACHINE-OPERATING MECHANISM.

Application filed August 18, 1924. Serial No. 732,885.

This invention relates to pressing machines, particularly machines such as are used in garment laundries, etc., and has for its object a particularly simple and efficient 5 operating and controlling means, by which the operator must use both hands to connect the power to the machine to close the press, so that, it is impossible for the operator to have one or both hands between the 10 pressing elements when the press is closing, and also by which if the operator releases his hold while the machine is closing the power will be automatically disconnected and the machine will stop.

15 The invention consists in the novel features and in the combinations and constructions hereinafter set forth and claimed.

In describing this invention reference is had to the accompanying drawings in which 20 like characters designate corresponding parts in all the views.

Figure 1 is a side elevation of a pressing machine embodying my invention.

Figure 2 is an enlarged front elevation 25 thereof.

Figure 3 is an enlarged elevation, partly in section of the controlling means.

Figure 4 is a detail view of one of the 30 parts of the differential gearing.

Figure 5 is a detailed sectional view of the clutch operated by the controlling means.

Figure 6 is a detail perspective view of the motion transmitting means between the 35 planetary member of the differential gearing and the shifting lever for the clutch.

This invention comprises, generally, a mechanism for controlling the closing of a pressing machine, such mechanism including two operator-operated members or handles, differential gear mechanism between the handles, whereby both must be operated fully either simultaneously or alternately, and if operated alternately the one first operated must be held in its operated position during the operation of the other lever, in order to cause the differential gear to transmit motion to the shifting lever.

I have here illustrated my invention as 50 embodied in a conventional type of pressing machine, including a lower stationary element or buck 1, and a movable pressing element or head 2, movable toward and from the buck 1, the buck being mounted 55 on a suitable bracket or goose neck 3 which

is supported upon a frame 4; and the head being carried by a yoke or lever 5 pivoted at 6 between its end to a standard 7 which is an extension of the rear leg or pedestal 8 of the frame of the machine.

The actuating means for the head 2 in addition to the lever 5, as here illustrated, comprises a toggle including links 9, 10, pivoted together at 11, and intermittent power actuated means to actuate the toggle. The 60 link 9 is pivoted at 12 to the rear arm of the lever 5, and the link 10 is pivoted at its lower end at 13 to the base of the frame, this lever 13 having a forwardly extending power arm 14 rigid therewith through 65 which the power is intermittently applied from a constantly running electric motor 15. The link 10 and power arm 14 form in effect a bell crank lever.

The motion of the armature shaft 16 of 70 the motor is transferred to the power lever 14 through suitable mechanism including a periodic or half revolution clutch. This motion transmitting mechanism comprises a shaft 17 journalled in a suitable housing 75 80 carried by the main frame 4 and connected by means of an eccentric or cam 19 and link 20 to the lever 14, a worm 21 is mounted on the armature shaft within the housing and meshing with the worm gear 22 85 rotatable about the shaft 17, and a clutch for connecting and disconnecting the worm gear 22 and the shaft 17.

This clutch may be of any suitable form, size and construction, and as here shown includes a shiftable section 23 mounted on the shaft 17 and shiftable axially thereof, and pins as the pin 24 shiftable by the section 23 into and out of holes as the hole 25 in the web of the gear 22. There are usually 90 a plurality as three pins 24 and also a plurality of holes 25. Usually there are three times as many holes 25 as there are pins, although but one pin and one hole are shown for illustrative purposes in the 95 drawing. The pins are guided in their movement by a guide disk 26 having passages through which the pins slide, this disk being arranged adjacent the worm gear 22. An intermediate pressure ring 27 100 thrusts at 28 against shoulders on the pins. Light springs 29 between the pressure ring and the section 23, yieldingly thrusts the pins into engaged position after the sections 23 has been initially shifted and a heavy 105

110

spring 30 thrusts against the section 23 to thrust it to its "out" position. The ends of the pins 24 and also the holes 25 are tapered, so that, the pins quickly release themselves from the holes 25 in the gear 22 when the force tending to hold them in the holes is discontinued. The light springs 29 serve to permit the pins 24 to yield when the section 23 is being shifted to the left and the pins are not in alinement with the holes and to thrust the pins into the holes when they come into alinement. The section 23 rotates with the shaft as the member 26 is keyed to the shaft and obviously the pins which are carried by this member 26 will cause the section 23 to be rotated with the member 26 and hence with the shaft 17.

The clutch section 23 is shifted against the action of the main spring 30 by means of a shifting lever 31, located in the housing or casing 18 mounted on the rock shaft 32 journaled in the housing, the lever 31 thrusting against the hub of the section 23. The section 23 is held in its "in" position by suitable means as a cam ring 33 fixed to the casing 18 concentric with the shaft 17, and having diametrically opposite notches 34 and plain faces 35, 35^a between the notches, and a follower 36 on the section 23 coaxing with the cam. Normally the follower 36 is located in the notches 34 and one of the plain faces as 35^a is preferably low at nearly the planes of the bottoms of the notches. Upon operation of the shaft 32 to shift the section 23 to the left, and hence shift the clutch "in", the follower is moved out of the depression and the pins 24 shifted into interlocking engagement with the driving worm gear 22.

By holding the handles depressed the clutch is held in during the closing of the press as the follower is opposite the low surface 35^a of the cam and if the operator releases one or both handles the clutch will throw out and the press head stop. After the shaft has made a half revolution the press is closed and the operator releases one or both hands from the handles. The operator determines by the feel of the machine when it is closed. After the press has remained closed as long as desired the operator momentarily depresses the handles until a follower rides on the high plane face 35 and the clutch is held in by the followers riding on the high plain face 35 until a follower again alines with the notches.

The clutch construction forms no part of this invention and any other suitable periodic mechanism may be used.

The means for controlling the shifting of the clutch section 23 comprises two manually operated members, differential gearing between the members, and motion transmitting means operated by the differential gearing.

The operating members are here shown

as a pair of handles 37, 38, mounted upon axially alined rock shafts 39, 40, which are mounted in suitable tubular housings 41 secured to the frame of the machine, and secured together by the differential gear housing as by clips or brackets 42. The rocking movement of these handles 37 and 38 is limited by the end walls 43 and 44 of the slots in the housing, through which slots the handles project. The differential gearing may be of any well known construction, and comprises side gears 45, 46 mounted respectively on opposing ends of the shafts 39 and 40, and planetary compensating pinions 47 carried by a carrier or ring 48, and meshing with the side gears 45, 46. The carrier 48 has an arm 49 extending through a slot 50 in the casing 51 for the gearing. This casing consists of sections mounted on the tubular housing 41.

The motion transmitting means between the differential gearing and the shifting lever 31 or the rock shaft 32 may be of any suitable form, size and construction, and as here shown consists of a link 52 connected at one end to the arm 49 and at its other end to one arm of a bell crank lever 53 pivoted in horizontal position to the frame 4, and a link 55 pivoted at one end to the other arm of the bell crank lever, and at its other end to a lever 56 mounted on a rock shaft 32. Upon depressing of one lever 37 or 38 the corresponding rock shaft 39, or 40, and hence, the side gears 45 or 46 thereon will be turned and the planetary or compensating pinions 47 will also be turned about their axes and transmit motion to the other side gear, and the other handle in the reverse direction, and no motion will be transmitted to the shifting lever 31. If both handles are depressed at the same time, the carrier 48 will be moved, thus actuating its arm 49 to shift the lever 31, and hence, shifts the clutch to its "in" position. Movement of one of the levers 37, 38 downwardly moves the other lever upwardly, and the operator by maintaining his hold on the lever first operated and then depressing the other lever will cause the shifting lever 31 to be shifted. In all cases both hands of the operator must be used at the same time to close the press.

What I claim is:

1. Means for controlling the application of power comprising a shiftable member, a pair of rock shafts arranged in axial alinement, a handle mounted on each shaft, gears mounted on the shafts respectively and a planetary equalizing gear coaxing with the former gears and connections between the planetary gear and the shiftable member for transmitting the planetary movement thereof to the shiftable member.

2. Means for controlling the application of power comprising a shiftable member

a pair of rock shafts, differential gearing between the rock shafts including a plan-
tarily movable equalizing member, and
means for transmitting the planetary
movement of such member to the operating
member.

3. In a pressing machine, the combina-
tion of coacting pressing elements, one mov-
able toward and from the other, power
means for actuating the movable element,
and means for controlling the application
of power to said element, comprising a
shiftable member, a pair of rock shafts,
each having a handle, differential gearing
between said shafts including a planetary
member, and motion transmitting connec-
tions between the planetary member and
the shiftable member.

4. In a pressing machine, the combina-
tion of coacting pressing elements, one 20
movable toward and from the other, power
means for actuating one of said elements,
and means for controlling the application
of power to the movable element, compris-
ing a shiftable member, a pair of rock 25
shafts, each having a handle, differential
gearing between said shafts including a
planetary member, motion transmitting connec-
tions between the planetary member and
the shifting member, and stops for limiting 30
the movement of the handles.

In testimony whereof, I have hereunto
signed my name, at Syracuse, in the county
of Onondaga and State of New York this
21st day of July, 1924.

ERNEST DAVIS.
